By H. G. Underwood
Attorney

UNITED STATES PATENT OFFICE.

HENRY J. NOLL, OF MILWAUKEE, WISCONSIN.

TRAIN-PIPE COUPLING.

SPECIFICATION forming part of Letters Patent No. 787,630, dated April 18, 1905.

Application filed August 19, 1904. Serial No. 221,350.

To all whom it may concern:

Be it known that I, HENRY JOHN NOLL, a citizen of the United States, and a resident of Milwaukee, in the county of Milwaukee and State of Wisconsin, have invented certain new and useful Improvements in Train-Pipe Couplings; and I do hereby declare that the following is a full, clear, and exact description thereof.

My invention has for its object to couple railway air-brake train-pipes, without interlocking connection; and it consists in certain peculiarities of construction and combination of parts hereinafter particularly set forth with reference to the accompanying drawings and subsequently claimed.

Figure 1 of the drawings represents a front elevation, partly in section, through the line 1 1 in Fig. 2 and illustrates a fragment of a railway-car provided with a train-pipe coupling in accordance with my invention; and Fig. 2, a sectional view of the same through the line 2 2 in Fig. 1.

Referring by letter to the drawings, A indicates a fragment of a railway-car, and B a socket in suspension from the car. The ball end *b* of a shank *c* engages the socket B, and said shank is a prolongation of a box C, containing a sliding barrel D and spiral spring E, this spring being under compression between the inner ends of the box and barrel. A stop-shoulder *d* of the barrel limits forward play of the same in the box, and said barrel has a depending nipple F in communication with its bore. The nipple has play in a longitudinal bottom slot *e* of the box, and a train-pipe G is coupled to the nipple. The forward end of the barrel D is expanded in all directions and trued to present a smooth face, having a slot *f* therein intersecting the bore of the remainder of said barrel, said bore being central of said slot.

The box C has vertical and lateral play within the confines of a bracket H depending from the car and is suspended by a cable or other suitable means from one end of a lever I, fulcrumed in said car and having a counterweight J hung from its other end. The bottom of the car is provided with an aperture *g*, in which the box-and-lever connection

has its play, and it is preferable, as herein shown, to inclose the lever and weight by a housing K in said car. Depending from the bracket H is a tubular guide L for another weight, M, connected by a flexible device *h* 55 with the under side of the box C, and the flexible hanger for the latter weight has play in an aperture of the otherwise-closed upper end of said guide. The weight J counterbalances the box, its contents, and the weight M, 60 said box being free to play at its front end in a vertical direction. The box is also free to play laterally at its front end against resistance of the weight M, that operates to automatically center said box counterbalanced by 65 the weight J aforesaid. However, means other than what is herein shown may be utilized for counterbalancing and automatically centering the box.

When cars are coupled, the opposing barrels D of a train-pipe coupling are moved one by the other to further compress the spring E back of each, the abutting ends of said barrels being then in close frictional contact, but free to play one against the other in all directions to compensate for the movements of said cars while running. Because of the slots *f* in the opposing ends of the coupling-barrels there is no interference with the flow of air in the connected train-pipes when said barrels 80 have vertical or lateral play, or both, one against the other.

Having thus described my invention, what I claim as new, and desire to secure by Letters Patent, is—

1. A train-pipe coupling consisting of a box in ball-and-socket counterbalanced self-centering connection with a car, a barrel having sliding engagement with the box, a depending barrel-nipple engaging a play-slot in said box, 90 and a spring under compression in the aforesaid box against the inner end of the barrel; the outer projecting end of said barrel being provided with a slot intersecting its bore.

2. A train-pipe coupling consisting of a box 95 having a shank end in ball-and-socket connection with the car, a lever from which the other end of the box is suspended, a counterweight hung from the lever, a barrel in sliding engagement with said box and provided with a 100

depending nipple engaging a slot in the same, a spring under compression in the aforesaid box against the inner end of the barrel, a weight in suspension by a flexible device from 5 the forward portion of the box, and a guide for the flexible device and suspended weight, the outer projecting end of the barrel being provided with a slot intersecting its bore.

In testimony that I claim the foregoing I have hereunto set my hand, at Milwaukee, in the county of Milwaukee and State of Wisconsin, in the presence of two witnesses.

HENRY J. NOLL.
